PROTECTIVE HOLDER FOR TOOTHBRUSH-
ES AND THE LIKE

Max Meyerson, New York, N. Y.

Application June 23, 1939, Serial No. 280,840

3 Claims. (Cl. 206—15.1)

This invention relates to devices for holding and protecting toothbrushes and the like whereby the brushes are maintained in good condition and protected from contamination.

5 The main object of the invention is to provide a holder of the character described whereby the bristles of the brush are protected from injurious contacts.

10 A further object of the invention is to provide a holder of the character described whereby the bristles of the brush are protected from injurious contacts, but which at the same time permits ready removal of the brush from the device.

15 A further object of the invention is to provide a holder wherein the bristle part of the brush shall be protected from accumulation of dust.

20 A further object of the invention is to provide a brush holder wherein there is a protective casing for the bristle part of the brush and means is provided to facilitate the ready drying of the brush.

25 A further object of the invention is to provide a holder of the character described comprising a casing for protecting the bristle part of the brush with means for preventing accumulation of moisture in the casing.

30 A further object of the invention is to provide a brush holder having a protective casing for the bristle part of the brush wherein means is provided for causing the circulation of air through the casing.

35 Other and ancillary objects of the invention will appear hereinafter.

35 In the accompanying drawing which illustrates the invention:

Fig. 1 is a front elevation, partly broken away, of a device embodying the invention;

40 Fig. 2 is a section on the line 2—2 of Fig. 1; Fig. 3 is a top plan view, partly broken away, of the device of Figs. 1 and 2;

Fig. 4 is a fragmentary, sectional view showing a modified form of fastening used in the structure of Figs. 1, 2 and 3;

45 Fig. 5 is a front elevation of a modified structure of holder; and

Fig. 6 is a section, partly broken away, on the line 6—6 of Fig. 5.

Referring to the drawing, and first to Figs. 1 to 4 inclusive, the device may be constructed of sheet metal, Celluloid or other suitable material.

The device comprises a ventilating chamber 1 having the back wall 2 with the up-standing projection 3 having a hole 4 by which the device 55 may be hung upon a nail or hook on a wall.

The chamber 1 comprises the side walls 5 having the ventilating holes 6 in its bottom and having the front wall 7. The chamber 1 is secured to a projection from a base or standard, the projection having the back wall 8 and the side walls 5 9 which project from and are secured to the base 10 which is tray-shaped, having the bottom 11 and the side walls 12, the forward part of the tray having a circular wall as at 13 conforming to the usual circular shape of a mug or tumbler 10 used in cleaning the teeth, and thus provides a suitable tray or holder for such glass or mug. The chamber 1 is secured to the base projection or pedestal by means of a metal pin or rod 14 extending through the side walls of the chamber 15 1 and also through the side walls 9 of the standard or base.

Instead of a rod 14 projecting continuously through from one side to the other of the device, the side wall 9 on each side may be secured to 20 the wall 5 of the chamber 1 in the manner as shown in Fig. 4, namely by inserting a pin 15 through the walls 5 and 9, such pin having a head 16 at one end and at the other end being screw-threaded and provided with a wing nut 17 25 by which the walls 5 and 9 may be securely fastened together.

At the front of the chamber 1 are arranged a plurality of casings 18 each comprising a top wall 19, a front wall 20 and side walls 21. The 30 bottom of the casing is formed by the wall 22 which projects forward from and is secured to the front wall 7 of the chamber 1. The casing part comprising the walls 19, 20 and 21 is pivoted so that it may occupy its closed position as shown 35 in full lines in Fig. 2 or be moved into the position as shown by dotted lines in Fig. 2, by means of a pivot pin or rod 23 extending through the side walls 21 of the protecting casing for the bristle part of the toothbrush and the walls 9 40 of the standard.

Secured to the wall 22 which extends continuously along and forms a bottom for all of the casings 18, and depending from such wall, is a tubular channel 24 for receiving the handles 45 25 of one or more toothbrushes, when the bristle part or parts 26 of the brushes are in the protective casing or casings as referred to. The channel piece 24 is of considerable length from top to bottom terminating within the side walls of 50 the tray 10, extending approximately across the width of the holder and is narrow from front to rear. This channel communicates with an opening 27 in the bottom 22 of the bristle part container casing and is open at its bottom so that 55

any moisture in the casing just referred to, either from the brush or for any other reason, may be drained out, while the circulation of air to dry and otherwise advantageously treat the bristles may circulate through the channel 24, the protective casing for the bristle part, the ventilating openings 28 into the chamber 1 and thence out through the openings 6.

In each of the casings 18 the bristle part of the brush is supported upon a tongue 29 projecting upwardly from the bottom 22 and it may be curved at its top as shown at 30. This affords, by coming in contact with the lower edge of the brush bristles, a means for supporting the bristles with a maximum of ventilating contact and also permits drainage of any moisture from the bristles so that the brush is maintained in the best condition.

Each of the casings 18 is preferably adapted to accommodate but one brush inasmuch as it is usually desirable to maintain each brush separate from the brushes used by other persons. However, it will be apparent that a casing might readily be enlarged so that several brush heads might be contained within one casing.

It will now be seen that each bristle part protective casing 18 may be turned forward on its pivot 23 into the position as indicated by dotted lines (Fig. 2) when a brush may be placed in or removed from position in the holder and that when the brush is so placed in position the casing 18 may be turned rearwardly into protective or closed position as indicated by the full lines in Fig. 2. The casing 18 is secured in its closed position by means of a spring tongue 31 secured to the wall of the casing and snapping into a slot or opening 32 in the front wall of the chamber 1.

In order to improve the tightness of the connection to keep out dust, moisture, etc., the front wall 7 of the ventilating chamber 1 may be provided with grooves 33 into which fit the top wall 19 and the side walls 21 of each protective casing. The holder as described may stand upon its base 11 upon a plane surface, or it may be supported upon a wall by a hook or nail in the wall passing through the opening 4.

Also the base portion might be detached from the ventilating chamber by removing the rod 14, and the ventilating chamber with its brush holding means might be supported on a nail or hook in the wall passing into the hole 4 as described. In the latter case the rear wall 2 of the ventilating chamber might be omitted, the wall upon which the device is supported then furnishing the back wall of the ventilating chamber.

Referring now to Figs. 5 and 6, the device therein shown comprises a ventilating chamber 34 open at the bottom and having its back wall provided with a hole 35 by means of which the holder may be suspended from a nail or pin in a wall.

At the front of the ventilating chamber are arranged a plurality of protective casings 36 for the brush part 37 of a toothbrush having the handle 38 projecting through an opening 39 in the bottom 40 of the protective casing, which

bottom is secured to the front wall 41 of the ventilating chamber, the brush handle 38 being exposed, that is, being provided with no enclosing chamber or casing. The brush is supported in the protective casing by means of a tongue 42 projecting upwardly from the bottom 40 and engaging with the lower end of the brush bristles. The bottom 40 also has the ventilating openings 43. The casing part enclosing the bristle part of the brush above the bottom 40, is hinged at 44 so that it may be moved upwardly to permit the brush to be placed in or removed from the holder, and when in its closed position is secured therein by a spring tongue 45 secured to the top wall 46 of the protective casing and snapping into an opening 47 in the front wall of the chamber 34.

It will thus be seen that the brush can readily be inserted into and removed from the holder, that the bristle part is thoroughly protected when in the holder, that ample provision is made by openings in the bottom of the protective casing for drainage of any moisture from that casing and that air may circulate through such bottom openings, the openings 48 in the front wall of the ventilating chamber and through the open bottom of the ventilating chamber 34 whereby the brush bristles are thoroughly dried and aerated.

While the invention has been illustrated in what are considered its best applications it may have other embodiments without departing from its spirit and is not therefore limited to the structures shown in the drawing.

What I claim is:

1. In a holder for tooth and other brushes, the combination with a protective casing for the bristle portion of the brush, said casing having an opening in its bottom for the passage of the brush handle and an elongated channel piece depending from the bottom of said casing for the reception of the brush handle, said channel piece being open at its lower end and communicating with the aforesaid opening.

2. In a holder for tooth and other brushes, the combination with a protective casing for the bristle portion of the brush, said casing having an opening in its bottom for the passage of the brush handle, said casing comprising a movable part which is movable to permit the brush to be inserted in and removed from said casing, said casing having a rear wall and a groove therein for receiving edges of the said movable part of the casing.

3. In a holder for tooth and other brushes, the combination with a plurality of protective casings for the bristle portions of the brushes, each of said casings having an opening in the bottom for the passage of a brush handle, and each of said casings comprising a movable part which is movable to permit the brush to be inserted in and removed from the casing and a channel part open at its lower end and communicating with the said handle openings in the bottoms of said casings.

MAX MEYERSON.
